UNITED STATES PATENT OFFICE.

PHILIP S. BRINDLE, OF COLUMBUS, OHIO.

DESIGN FOR A GAS-STOVE.

SPECIFICATION forming part of Design No. 33,476, dated October 30, 1900.

Application filed August 2, 1900. Serial No. 25,723. Term of patent 7 years.

To all whom it may concern:

Be it known that I, PHILIP S. BRINDLE, a citizen of the United States, residing at Columbus, in the county of Franklin and State 5 of Ohio, have invented and produced a new and original Design for Gas-Stoves, of which the following is a specification, reference being had to the accompanying drawings, forming part thereof.

Figure 1 is a front elevation of a stove having my new design, and Fig. 2 is a side elevation of the same.

As shown in the drawings, the leading or material feature of my design consists in the 15 burner-back *a*, having a tapering or substantially keystone shape and provided with a rough surface. This burner-back rises from a horizontal stove-base and is surmounted by

a semidome-shaped top plate *b*, the latter having a flaring base-skirt on its front and sides, 20 as indicated at *c*. Between the corner portions of the top plate *b* and similar portions of the base *d* are frame-standards *e*. Supported between the standards *e* at the front is an ornamental frame of scrollwork *f*, similar scroll-frames *g* extending between the standards *e* at the sides. 25

Having described my invention, what I claim as new, and desire to secure by Letters Patent, is—

The design for a gas-stove as herein shown and described. 30

PHILIP S. BRINDLE.
